UNITED STATES PATENT OFFICE.

JOHN S. STEPHENS, OF PATERSON, NEW JERSEY.

LOCK FOR TELEPHONES.

1,186,049.

Specification of Letters Patent.

Patented June 6, 1916.

Application filed June 2, 1915. Serial No. 31,711.

To all whom it may concern:

Be it known that I, JOHN S. STEPHENS, a citizen of the United States, residing at Paterson, in the county of Passaic and State 5 of New Jersey, have invented certain new and useful Improvements in Locks for Telephones, of which the following is a specification.

This invention contemplates an improved 10 telephone lock and has as its primary object to provide a device of this character adapted for attachment to any conventional type of telephone for preventing the unauthorized use thereof.

15 The invention has as a further object to provide a device of this character adapted to fit around the stem of a telephone to engage within the slot formed therein upon one side of the receiver hook to prevent the 20 release of the hook upon the removal of the receiver therefrom. And the invention has as a still further object to provide a device of this character adapted to coöperate with the hook in such manner that upward force 25 upon the hook tending to move it to released position will act to urge the device into more secure locking engagement within the slot receiving the hook and consequently prevent the release of the hook.

30 Other and incidental objects will appear as the description proceeds and in the drawings wherein I have illustrated the preferred embodiment of the invention and wherein similar reference characters designate 35 responding parts throughout the several views, Figure 1 is an elevation showing my improved device applied to a conventional type of telephone, Fig. 2 is a fragmentary sectional view particularly showing the 40 manner in which the device is adapted to engage the receiver hook of the telephone, Fig. 3 is a perspective view of the lock detached, and Fig. 4 is a plan view showing the manner in which the device is applied 45 to a telephone.

In carrying out my invention, I employ a lock including a body portion or casing 10 to which is slidably connected a shackle 11. The casing 10 and internal mechanism of 50 the lock may be of any conventional type, the said mechanism being adapted to coact with the shackle 11 when the shackle is moved to engage therewith, in the well known manner. In this connection, it may 55 be stated that the shackle 11 may be either slidably connected with the body of the lock,

as shown in the drawings, or may be pivotally connected thereto in conventional manner.

As particularly illustrated in Figs. 3 and 4 of the drawings, the shackle is substantially U-shaped in general conformation and includes substantially parallel arms 12 which are joined by a curved connecting or bight portion 13, the arms 12 being adapted to be slidably received within the body portion 10 of the lock to coöperate therewith. Formed on the bight portion 13 of the shackle at a point substantially midway its ends, is a laterally and inwardly extending 70 tongue 14 having, upon one side thereof a beveled face 14'. As will be noted, the tongue 14 is arranged in a plane with the arms 12 of the shackle and extends toward the body portion 10 of the lock.

75 Depending from the bight portion 13 of the shackle and extending laterally therefrom at substantially right angles to the tongue 14 are spaced ears 15 which define an intermediate slot 16, arranged in a plane 80 with the tongue 14. The ears 15 as will be observed, are transversely curved or may be provided with inner curved faces conforming in general outline to the curvature of the bight portion 13 of the shackle.

85 In order that the function and use of my improved lock might be more clear, I have, in the drawings, illustrated a conventional type of telephone having a base 17. Rising from the base 17 is a cylindrical stem 18 90 upon the upper extremity of which is arranged a transmitter 19. Projecting laterally from the stem 18 upon one side thereof, is a spring actuated receiver hook 20 which extends freely through a suitable slot 21 95 formed in the wall of the stem and is adapted to detachably carry the receiver 22 in the usual manner.

100 The receiver 22 is normally supported by the hook 20 so that the hook will be depressed within the slot 21 as best shown in Fig. 2 of the drawings, the said slot being of a length of course, to permit of the upward pivotal movement of the said hook to complete an electrical circuit through the 105 telephone. The device of the present invention may then be applied in the manner illustrated in Fig. 4 of the drawings. The mechanism of the lock is actuated by a suitable key to release the shackle 10 when the 110 arms of the said shackle are withdrawn from the body portion 10 of the lock as

therein illustrated. The shackle is then arranged to embrace the stem 18 of the telephone and is positioned above the receiver hook 20 whence the tongue 14 of the shackle is inserted within the slot 21 as more particularly shown in Fig. 2 of the drawings with the hook 20 extending freely within the slot 16 defined by the ears 15.

The tongue 14 is adapted to be freely received within the slot 21, as shown in Fig. 2 of the drawings and is further adapted to be urged to a position to entirely fill the space between the upper edge of the receiver hook 20 and the upper end wall of the said slot for securely holding the receiver hook in depressed inoperative position, while the ears 15 are adapted to conform to the contour of the stem 18 to engage therewith upon each side of the hook. After the shackle has been thus engaged with the telephone, the body portion 10 of the lock is moved into operative engagement with the arms 12 of the shackle to assume the position shown in Figs. 1 and 2 of the drawings and thus permanently connect the lock with the telephone pending its authorized removal.

It will now be noted that the body portion 10 of the lock, when the device is operatively connected to the telephone, is adapted to coöperate with the stem 18 thereof to prevent any lateral shifting of the lock upon the telephone such as would permit the tongue 14 to be displaced from the slot 21. Consequently, it will, in use, be necessary to first release the shackle 11 to effect the displacement of the tongue. Furthermore, it will be observed that when the lock is applied, the beveled face 14' of the tongue 14 is arranged to confront the upper edge of the receiver hook 20 with the receiver hook normally engaging the said tongue immediately adjacent the inner end thereof. Accordingly, upward pressure or force exerted upon the hook 20 tending to move it to operative position within the slot 21 and consequently close an electrical circuit through the telephone will cause the said hook to so engage the tongue 14 of the shackle, that the said tongue will tend to pivot at its inner extremity upon the hook to assume a position with the beveled face 15 thereof seating flatly against the upper edge of the hook. Such pivotal movement of the tongue 14 will, of course, tend to urge the body portion 10 of the lock upwardly and will, at the same time, tend to urge the ears 15 to engage at their outer extremities with the stem 18 of the telephone. The body portion 10 of the lock will then normally gravitate to return the tongue 14 to its normal position as shown in Fig. 2 of the drawings but this action will be counteracted by the engagement of the tongues 15 with the stem of the telephone. It will

therefore be seen that such upward pressure upon the receiver hook 20 can only act to cause the shackle and lock to pivot or fulcrum upon the outer extremities of the ears 15 which movement will in turn, tend to urge the tongue 14 inwardly within the slot 21 and consequently wedge or more securely bind therein to hold the receiver arm 20 depressed.

From the preceding description, it will be observed that I thus provide a very simple and efficient construction for the purpose set forth adapted to prevent the unauthorized use of a telephone and which may be employed in connection with any telephone of conventional type without the necessity of structural change therein. Owing to the presence of the ears 15 upon the shackle, tampering with the shackle to effect the unauthorized displacement of the tongue 14 from within the slot 21 will be prevented while, when the receiver 22 is removed from its hook, the spring tension upon the hook urging it into engagement with the tongue 14 will normally tend to urge the tongue into more secure locking engagement with the telephone.

Having thus described my invention, what I claim and desire to secure by Letters Patent is:

1. A lock for telephones including a shackle, a tongue carried by the shackle and provided with a beveled face, and depending ears carried by the shackle and adapted to coöperate with the tongue, the shackle being adapted to embrace the stem of a telephone with the said tongue engaging within the receiver hook slot formed in the said stem upon one side of said hook and with the said ears adapted to engage the stem upon one side of said tongue, the beveled face of the tongue being arranged to confront the upper edge of the hook to normally engage at its free extremity therewith, and a lock arranged to coöperate with the shackle.

2. The combination with a telephone having a stem provided with a slot, and a receiver hook projecting freely through said slot, of a shackle embracing the stem and provided with a lock coöperating therewith, a tongue carried by the shackle and arranged to engage in said slot with the body portion of the lock body adapted to coöperate with the stem to prevent the longitudinal displacement of the tongue from the slot, the said tongue being formed with an inner beveled face arranged to confront the upper edge of said hook with the free extremity of said tongue normally engaging the hook, and spaced ears depending laterally from the shackle and adapted to engage the stem upon one side of said tongue, the said ears defining an intermediate slot freely receiving the hook.

3. A lock for telephones including a shackle, a tongue carried by the shackle, and a lock body arranged to coöperate with the shackle, the shackle being adapted to embrace the stem of a telephone with said tongue extending within the receiver hook slot formed in the said stem to engage at its free extremity with the hook and with the lock body for holding the tongue against the lock body engaging the stem for holding 25 the tongue against outward shifting movement within the said slot and normally gravitating to fulcrum the tongue at its inner end upon the hook.
5. A lock for telephones including a shackle, a tongue carried thereby, and a lock body arranged to coöperate with the shackle and having its edge confronting the shackle cut away, the shackle being adapted to embrace the stem of a telephone with said 30 tongue extending within the receiver hook slot formed in the said stem to engage at its free extremity with the hook and with the cut away portion of the lock body fitting around the stem for holding the tongue 35 against outward shifting movement within the said slot with the lock body supported to extend laterally from the stem and normally gravitating to fulcrum the tongue at its inner extremity upon the hook. 40 45
4. A lock for telephones including a shackle, a tongue carried by the shackle, an ear depending from the shackle and adapted to coöperate with the tongue, and a lock body arranged to coöperate with the shackle, the shackle being adapted to embrace the 15 stem of a telephone with said tongue extending within the receiver hook slot formed in the stem to engage at its free extremity with the hook with the said ear abutting the stem below the tongue and with one edge of

In testimony whereof I affix my signature,
JOHN S. STEPHENS. [L. s.]
